CLAIM

The ornamental design for a speaker device, as shown and described.

DESCRIPTION

FIG. 1 is a top perspective view of a speaker device showing our new design;

FIG. 2 is a bottom perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines immediately adjacent the shaded areas represent the bounds of the claimed design while all other broken lines are directed to unclaimed portions and are for illustrative purposes only; the broken lines form no part of the claimed design.

1 Claim, 6 Drawing Sheets

Related U.S. Application Data

continuation-in-part of application No. 29/615,773, filed on Aug. 31, 2017, now abandoned, and a continuation-in-part of application No. 29/615,769, filed on Aug. 31, 2017, now abandoned.
